US00D819424S

(12) **United States Design Patent** (10) **Patent No.:** **US D819,424 S**
Graykowski et al. (45) **Date of Patent:** **** Jun. 5, 2018**

(54) **WIRE STRIPPER**(71) Applicant: **Milwaukee Electric Tool Corporation**,
Brookfield, WI (US)(72) Inventors: **Anthony S. Graykowski**, Port
Washington, WI (US); **Matthew A.**
Lownik, West Allis, WI (US)(73) Assignee: **MILWAUKEE ELECTRIC TOOL**
CORPORATION, Brookfield, WI (US)(**) Term: **15 Years**(21) Appl. No.: **29/592,664**(22) Filed: **Feb. 1, 2017**(51) LOC (11) Cl. **08-02**(52) U.S. Cl.
USPC ..... **D8/98**(58) **Field of Classification Search**USPC D8/5, 14, 45, 44, 50, 51, 98, 105, 107,
D8/90, 300; D19/65; D24/133
CPC ... H02G 1/1212; H02G 1/1214; H02G 1/1224
